UNITED STATES PATENT OFFICE

23,289

TIRE CHAIN RELEASE DEVICE

Milton B. Herbrick, Sterling, Colo.

Original No. 2,472,828, dated June 14, 1949, Serial No. 7,146, February 9, 1948. Application for reissue June 2, 1950, Serial No. 165,825

6 Claims. (Cl. 152—213)

Matter enclosed in heavy brackets **I** appears in the original patent but forms no part of this reissue specification; matter printed in italics indicates the additions made by reissue.

I

My invention relates to a tire chain device.

An object of my invention is to provide a release device which will allow a tire chain to be released from a tire, and whereby the inner side chain can be conveniently removed.

A further object of my invention is to provide means for releasing the inner chain in a simple arrangement which requires very few parts, and which works cooperatively with the end cross chain for the releasing function.

A further object of my invention is to provide a device having the above characteristics which can be readily attached, or detached.

With these and other objects in view, my invention consists in the construction, arrangement, and combination of the various parts of my device, whereby the objects contemplated are attained, as hereinafter more fully set forth, pointed out in my **[claim]** claims, and illustrated in the accompanying drawings, in which:

Figure 1 is a side elevation of one form of the releasing device as observed from the inside of a tire.

Figure 2 is a sectional detail taken along the lines **2—2** of Figure 1.

Figure 3 is a modification, and

Figure 4 is a side view of Figure 3.

My invention contemplates a simple arrangement for detaching the inner, annular side chain of a tire chain arrangement, which arrangement is operatively connected with one of the cross chains.

I have used the character **10** to designate the inner side wall of a tire casing, or the side which is facing away from the outside of the vehicle. I have further used the character **11** to designate a series of chain links which provide the inner side chain of the chain arrangement, and I have used the character **12** to designate the usual *twisted* cross links which straddle the tire **13**, such cross links being attached at **14** to either side, it being understood that a further series of links **11** are positioned on the outside of the tire. I have further used the character **15** to designate the end cross chains including the aforesaid twisted links **12**. **[The cross chains 15 are attached at their outer ends to the commonly used ring or clamp, which provide attaching means for attachment to the end link 11 of the outside chain.]** The cross chain **15** is attached at its outer end to the commonly used ring or clamp which provides attaching means for attachment to the end link **11** of the outside chain. This construction is well-known in the art and need not be illustrated herein.

2

One of the end links **11** is attached at **16** to the ring shaped member **17** having an opening at **18**. Attached to an end link **12** of the cross chain is a keeper link **19** which is attached at **20** to the arcuate cam or wedging member **21** which is approximately as wide as the inner diameter of the ring **17**. Attached at **22**, or extending from the wider portion **21** is the considerably reduced portion **23** which is bent at **24**, and is attached at **25** to the member **21**.

Figure 1 illustrates the arrangement as attached, and with the further end link **11** being firmly held within the ring member **17** due to the fact that the expanded portion **21** has compressed the end link **11** within the member **17**, the member **21** being held securely in this position due to the fact that the cross chain member **15** is attached in place.

However, when it is desired to remove the chain from the tire, the outer end of the cross chain **15** is detached from the outer side wall chain, and next, the operator will then be allowed to swing the member **21** in the direction of the arrow **26** until the reduced portion **23** is within the ring **17**. This operation will allow the right hand link **11** as shown in Figure 1 to be removed through the opening **18**, thereby releasing the inner side wall chain, whereby the chain can be removed. This, then, provides a simple means for releasing the inner side wall chain, and if desired, the arrangement in some cases can be swung by means of the cross chain itself, or by grasping the member **19**.

A further modification of this arrangement is shown in Figures 3 and 4 wherein the same ring **17** is employed and having the opening **18** and with the links being attached in the same manner. In this arrangement, however, a member having a circular cross section and which is indicated by the character **27** at its greatest cross section is used, and terminates in the expanded head **28** which bears against the tire casing **13**. The portion **27** continues into the reduced portion **29** which is substantially arcuate as shown, the lower end of which is attached at **30** to a further link or keeper **31** which in turn is attached to the links **12** of the cross chain. In this latter construction, when it is desired to release the side wall chains, after the cross chain **15** is released, the members **29** and **27** are pivoted in the direction of the arrow **26** whereby the reduced portion **29** will enter into the ring **17**, allowing the link **11** to be released through the opening **18** in the same manner as described above. The **55** arcuate portion **29** permits the pivoted or oscilla-

tory movement of the wedge member 27 by the cross chain 15 which, when released, is swung outwardly to operate the chain release device.

It will now be seen that I have provided the various advantages set forth in the objects of my invention with various other advantages being readily apparent.

Some changes may be made in the construction and arrangement of the parts of my invention without departing from the real spirit and purpose of my invention, and it is my intention to cover by my [claim] claims any modified forms of structure or use of mechanical equivalents which may be reasonably included within their scope.

I claim as my invention:

1. **[A** tire chain release device including an inner side chain divided and forming two end portions, a cross chain, and clamp means including a ring connected to one end portion of the inner side chain, said ring having a releasing opening, said ring receiving a link of the other end portion of the side chain, wedging members received in said ring adapted to snugly retain said link within said ring member, said wedging members having reduced portions, and being attached to said cross chain whereby release of said cross chain will provide means for reception of said reduced portions within said ring to allow release of said link through said releasing opening for releasing said inner side chain from a tire.]

2. A tire chain release device including an inner side chain divided and forming two end portions, a cross chain and clamp means including a ring connected to one end portion of the inner side chain, said ring having a releasing opening, said ring receiving a link of the other end portion of the side chain, a wedging member received in said ring adapted to snugly retain said link within said ring member, said wedging member having a reduced portion and being attached to said cross chain whereby release of said cross chain will provide means for reception of said reduced portion within said ring to allow release of said link through said releasing opening for releasing said inner side chain from a tire.

3. A tire chain release device for an inner side chain divided and forming two end portions, said tire chain release device comprising a ring member detachably connecting the end portions of the inner side chain and having a releasing opening and a cooperating member extending through the ring member, said members having relative oscillatory movement to effect release of one of the end portions of the inner side chain from the other through said releasing opening, and a cross chain connected to one of said members for effecting said oscillatory movement.

4. A tire chain release device including an inner side chain divided and forming two end portions, said tire chain release device detachably connecting the end portions of the inner side chain and comprising a connecting member connected with one of the end portions of the inner side chain and having a portion engaging a link of the other end portion of the inner side chain whereby the two end portions of the inner side chain are detachably connected together,

and a cooperating member mounted on the connecting member for pivoted or oscillatory movement in a direction transversely of the connecting member and maintaining the connected end portions of the inner side chain in such connected relation, and a cross chain connected to said cooperating member and adapted, when free, to oscillate the same in a direction transversely of the connecting member to effect release of one of the end portions of the inner side chain from the other.

5. A tire chain release device including an inner side chain divided and forming two end portions, said tire chain release device detachably connecting the end portions of the inner side chain and comprising two interfitting members, one of said members having a pivoted or oscillatory movement in a direction transversely of the other member from one position to a second position and in one position maintaining the end portions of the inner side chain connected together and in the second position effecting a release of one end portion of the inner side chain from the other through a release opening controlled by said oscillatory movement, and a cross chain connected with one of said members to effect the said pivoted or oscillatory movement thereof for operating the chain release device.

6. A tire chain release device including an inner side chain divided and forming two end portions, said tire chain release device detachably connecting the end portions of the inner side chain and comprising two interfitting members, one of said members having a pivoted or oscillatory movement from one position to a second position and in one position maintaining the end portions of the inner side chain connected together and in the second position effecting a release of one end portion of the inner side chain from the other, and one of said members consisting of a ring having a releasing opening, and a cross chain connected to the member having the said pivoted or oscillatory movement for operating the the release device to effect the release of one end portion of the inner side chain from the other through the said releasing opening.

7. A tire chain release device for an inner side chain divided and forming two end portions, comprising a ring secured to one end portion and provided with a release opening and a cooperating member extending through the ring and movable transversely thereof and maintaining the other end portion of the inner side chain connected to the ring, said members having relative oscillatory movement to effect release of one of the end portions through the release opening.
